Inventor:
Charles P. Marshall,
By Knight & Co, Atty.

UNITED STATES PATENT OFFICE.

CHARLES P. MARSHALL, OF MEMPHIS, TENNESSEE.

AIR-REFRIGERATING APPARATUS.

SPECIFICATION forming part of Letters Patent No. 310,212, dated January 6, 1885.

Application filed May 14, 1884. (No model.)

To all whom it may concern:

Be it known that I, CHARLES P. MARSHALL, a citizen of the United States, residing at Memphis, in the county of Shelby and State 5 of Tennessee, have invented certain new and useful Improvements in Air-Refrigerating Apparatus, of which the following is a specification.

The object of the present invention is to cool the air of a refrigerator or railroad-car or other chamber by passing the warmer air of the top of the compartment continuously into and around an ice-chest, the arrangement of the apparatus being such that circulation of the warm air from the compartment into the top of the ice-chest and of the cold air from the bottom of the ice-chest into the compartment is continuously effected. To this end I place the ice-chest in any suitable 15 part of the compartment, and provide it with one or any number of air-pipes, to which air is supplied from the top of the compartment by hoods suitably arranged. The sides of the chest are made double, open at bottom, 20 and provided at top with means of access of the warmer air, which entering the jacket and striking the cold sides of the ice-chest will descend into the lower part of the compartment to be cooled, and thus maintain a 25 constant circulation of air. Ordinary traps are provided for the escape of water from the ice-chest, protected by a metallic guard in a manner subsequently to be described.

In order that my invention may be fully 35 understood, I will proceed to describe it with reference to the accompanying drawings, in which—

Figure 1 is a plan of the improved refrigerating apparatus, part of the top being broken 40 away and the cover being removed to show the arrangement of the air-pipes. Fig. 2 is a vertical section of the same on the line II—II, Fig. 1. Fig. 3 is a vertical section on the line III—III, Fig. 2.

1 may represent any space or chamber the air of which it is desired to cool.

2 is an ice-chest, here shown supported from the roof of the chamber and from one of the sides thereof and covered by a hinged 50 door, 2^a. The sides of the ice-chest are double-

walled, as shown, the jacket thus formed being open at bottom for the free egress of cold air. Access of the warm air of the top of the chamber to the jackets 3 is provided by pipes 4 and 6, having hoods 7, and by inlet-ports 55 11 and 12 in the walls. The pipes 4 6 communicate with the rear jacket, the inlet 11 with the front one, and the inlets 12 with the sides. The inlet 11 is made the full width of the ice-chest. It will be seen that the warm 60 air from the top of the refrigerating-chamber entering these inlets will strike the cold walls of the ice-chest, and descending through the open bottom of the jacket will maintain a constant circulation of air throughout the compartment. Vertical pipe or pipes 8 are arranged within the ice-chest, and receive air from the top of the refrigerating-chamber by pipe 5 and hood 7. The pipe or pipes 8 have an elbow, 13, at bottom for directing the cold 70 air falling through said pipe or pipes out into the chamber.

10 is a diaphragm placed transverse of the refrigerating-chamber near its top, so as to deflect all the warm air rising in the compartment into one or the other of the hoods 7 or 75 apertures 11 12.

14 14 are customary traps permitting the escape of water from the ice-chest, and 14^a is a perforated metal plate divided at center 80 for convenience of insertion into or removal from the ice-chest. The purpose of said plate is to prevent the ice from resting upon and clogging the traps. The water falling from the traps is caught by pan 15 and led 85 into trough 16, whence it is discharged by pipe 17.

18 is a fan, which is placed above the diaphragm 10 and arranged to draw air out of the chamber 1 into the eye of the fan and discharge it through the pipes 5 8, thus increasing the rapidity of circulation and the rarefaction of air within the chamber 1.

Having thus described my invention, the following is what I claim as new therein and 95 desire to secure by Letters Patent:

1. The combination, with the ice-chest 2, having double jackets 3, open at bottom, as described, of the pipes 4 6, passing through the ice-chest 2 and opening into the space between 100

the jackets on the opposite side thereof, as and for the purpose set forth.

2. The combination of ice-chest 2, double-jacketed, as shown, pipes 4 6, having hoods 7, and ingress-ports 11 12, substantially as and for the purpose set forth.

3. In combination with pipes 4 5 6 and hoods

7, the diaphragm 10 for deflecting the air rising in the compartment into said hoods, as shown and described.

CHAS. P. MARSHALL.
